CLAIM

The ornamental design for a nail file having a handle, as shown and described.

DESCRIPTION

FIG. 1 is a perspective view of a nail file having a handle showing my new design;

FIG. 2 is a front elevational view thereof;

FIG. 3 is a top plan view thereof;

FIG. 4 is a bottom plan view thereof;

FIG. 5 is a side elevational view, the opposite side being a mirror image; and,

FIG. 6 is a rear elevational view thereof.
